US00D626957S

(12) **United States Design Patent**
Juan et al.

(10) **Patent No.:** US D626,957 S
(45) **Date of Patent:** ** Nov. 9, 2010

(54) **ELECTRONIC BOOK**

(75) Inventors: **Chien-Ming Juan**, Taipei (TW);
Chang-Ta Miao, Taipei (TW);
Gwo-Chyuan Chen, Taipei (TW)

(73) Assignee: **Quanta Computer Inc.**, Taoyuan Shien (TW)

(**) Term: **14 Years**

(21) Appl. No.: **29/347,739**

(22) Filed: **May 3, 2010**

(30) **Foreign Application Priority Data**

Mar. 22, 2010 (TW) 99301385

(51) **LOC (9) Cl.** 14-02

(52) **U.S. Cl.** **D14/345**
